UNITED STATES PATENT OFFICE

FRANCIS DEVINS, OF NEW YORK, N. Y.

PRICE-TICKET HOLDER

Application filed June 15, 1928. Serial No. 285,607.

This invention relates to a holder for displaying price tickets, cards and other closely analogous articles.

More particularly the invention relates to a type of holder such as the one disclosed in my pending application, filed March 21, 1928, and having Serial Number 263,429.

The principal object of this invention is to so construct parts of the holder of the type referred to, as to facilitate the removal of the ticket or card, to thereby improve the holder in this respect.

The nature of the invention and its distinguishing features and advantages will appear when the following specification is read in connection with the accompanying drawing, in which—

Figure 1 is a front view of the holder with a price card in place.

20 Fig. 2 is a back view of the holder.

Fig. 3 is a sectional view taken on the line 3—3 of Fig. 2, showing the holder attached to the edge of a support in displaying position.

25 Fig. 4 is a sectional view similar to Fig. 3, but showing a relationship of parts which will permit the price card to be poked out of its normal position.

Fig. 5 is a sectional view taken on the line 30 5—5, of Fig. 2.

Referring now more particularly to the drawing, it will be apparent that the holder of the present invention comprises two main parts, a part 10 and a part 11, together with 35 means which cooperatively associates the parts 10 and 11 with each other so as to removably hold a price ticket or card, and also so as to enable the attachment of the holder to the edge of a table, shelf, counter or like 40 support in a position to display the price ticket or card. In the present instance the parts 10 and 11 are so formed as to enable a person to readily manipulate or flex the price ticket or card so that the same may be 45 gripped for the purpose of removing the ticket or card from the holder.

The part 10 is stamped, bent and formed from a single piece of sheet metal to provide a plate or main flat body 12 having a channel 50 13 on each of the side edges, which terminates

short of the top edge thereof, at the front of the body 12, a channel at the lower edge of the body 12 centrally thereof, a channel 15 on each of the side edges at the back of the body 12 at the top thereof, oval shaped poke 55 holes 16, an apertured lug 17 struck from the center of the body 12 and disposed rearwardly thereof, and a gripping member 18 on the lower edge of the body 12 disposed rearwardly thereof.

The part 11 is stamped, bent and formed from a single piece of sheet metal to provide a plate or flat body 19 having a channel 20 on the upper edge thereof which extends entirely across the body 19, a gripping member 21 on the lower edge of the body 19 disposed rearwardly thereof, and there being an opening 22 centrally of the body 19, and circular poke holes 23 in the body 19 respectively at opposite sides of the opening 70 22. The part 11 thus constructed is adapted to be associated with the part 10, the opposite side edges of the body 19 being received respectively in the channels 15, with the lug 17 extending through the opening 22, and the poke holes 23 in registration respectively with the poke holes 16, the said holes 16 and 23 being in alignment for that purpose. The parts 10 and 11 are thus held for relative movement with respect to each other.

In order to set up a clamping or gripping action between the gripping members 18 and 21 there is provided a pin 24 rigidly connected with the gripping member 21, and the said pin extends through the hole in the lug 17 on the body 12 of the part 10. A spring 25 surrounds the pin 24 and has one end thereof in engagement with the gripping member 21 and the opposite end thereof is in engagement with the lug 17. It will now 90 be apparent that by moving the part 11 relatively to the part 10, the gripping member 21 may be moved away from the gripping member 18 to accommodate the edge of a suitable support, such as the edge of a table, shelf or the like, the holder in its entirety being held in a displaying position by the gripping members 18 and 21, which are constantly under the action of the spring 25.

The part 10 of the holder serves for sup-

100

porting a price ticket or card, such as the one designated 26, the said ticket or card being held in place by the channels 13 and 14 which receive the opposite side edges respectively 5 and the lower edge of the ticket or card. The channel 20 on the body 19 of the part 11 receives the upper edge of the ticket or card 26, and the said ticket or card is thus held against displacement.

10 When it is desired to remove the ticket or card 26 from the holder, the part 11 is moved relatively to the part 10 so as to disengage the channel 20 from the upper edge of the ticket or card. The ticket or card may then 15 be manipulated by poking one of the fingers of the hand through the registering holes 16 and 23; to flex the disengaged edge of the ticket or card from its normal position as shown in Fig. 4. The upper edge of the ticket 20 or card may then be readily gripped for the purpose of removing the ticket or card from the channels 13 and 14 of the part 10.

I claim:

1. In a holder, two relatively movable 25 spring actuated cooperating parts so constructed as to hold an indicia bearing card displayed, said parts having an arrangement of poke holes whereby the card may be readily poked out of its normal position, so that 30 the card may be gripped for the purpose of removing the card from the holder.

2. In a holder, two cooperating parts having channels relatively disposed for receiving the edges of an indicia bearing card, 35 said parts being movable relatively to each other to thereby disengage the channel of one of said parts from the related edge of the card, said parts having an arrangement of poke holes which register with each other 40 whereby the disengaged edge of the card may be flexed from its normal position so that said edge may be gripped for the purpose of removing the card from the holder.

Signed at New York, in the county of 45 New York and State of New York this 14th day of June, 1928.

FRANCIS DEVINS.
